UNITED STATES PATENT OFFICE.

LEWIS A. DARLING, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

CONTROLLING VALVE.

Application filed June 18, 1919. Serial No. 305,125.

To all whom it may concern:

Be it known that I, LEWIS A. DARLING, a citizen of the United States, residing in the city and county of Philadelphia and State 5 of Pennsylvania, have invented certain new and useful Improvements in Controlling Valves, whereof the following is a specification, reference being had to the accompanying drawings.

10 My invention relates to controlling valves especially adapted for motor devices such as steam turbine generators, and to the actuation of such valves. It is my aim to make the valve structure and mechanism simple 15 and easy to assemble, take apart, or adjust; free from derangement in service; and easy and economical to manufacture. How these and other advantages can be obtained in connection with my invention will appear from 20 the description hereinafter of the best embodiment of the invention at present known to me, while its scope and essentials will be indicated in my claims. The invention is especially desirable for steam turbo generators 25 used for operating electric headlights of steam locomotives.

In the drawings, Fig. I, is a view of the valve and its actuating mechanism in elevation, the enclosing structure being shown 30 partly in section.

Fig. II, shows a cross-section of the valve proper at the line II—II, in Fig. I.

Fig. III, is a plan view of a valve actuating or operating part.

35 As here shown, the turbine structure has a casing 1, with a side pocket that communicates with the main turbine chamber containing the bucket wheel or rotor (not shown). In an opening in the upper portion 40 of the casing 1, is secured a fixed structural system or group of parts that affords a mounting for the valve body 2, and the associated operating parts. This system includes a sleeve 3, with internal passages 4 45 and 5, at different longitudinal intervals or levels, and, in this instance, a cap 6, shown as separate from the sleeve 3. The passages 4, receive the steam from the supply pipe 7, through a corresponding passage 8, in the casing 1, and the passages 5, deliver it to the turbine wheel through the corresponding passage 9, in said casing 1, and the nozzles 10. The opening in which the sleeve 3, is mounted includes or intersects overlap-

ping portions of the passages 8 and 9, and 55 also an additional overlapping passage 11, that communicates with the turbine wheel space or chamber. The internal bore of the sleeve 3, opens into this passage 11, so that the corresponding end of the valve body 2, 60 is exposed to the pressure therein.

The sleeve passages 4 and 5, it will be seen, open into deep grooves 12 and 13, in the inner wall of the sleeve bore. The valve body 2, shown is in the form of a solid, one-piece piston valve, with a reduced middle portion of sufficient length to overlap the grooves 12 and 13, simultaneously and permit the steam to pass freely therearound, unthrottled, from the passages 4, to the passages 5. The enlarged ends or heads of this valve body 2, are of the same width and have packing and lubricating grooves for taking advantage of the packing action of the water in the steam and insuring good lubrication of the adjacent relatively movable surfaces. The valve has at its ends similar actuating rod members 15 and 16, (here shown as substantially identical), projecting endwise from the heads. It is, therefore, reversible end for end and substantially symmetrical. Its lower end, it will be seen, is freely exposed in a chamber 17, formed by enlargement of the sleeve bore, and the corresponding actuating rod 16, extends out loosely through a relatively large hole in this end of the sleeve 2, so that the chamber 17, is in free communication with the pocket at 1, and with the turbine wheel chamber. Hence the valve body 2, is completely balanced, as well as reversible, end for end, in respect of all its functions, since both its piston heads and its actuating rods are, respectively, substantially counter-parts of one another. A shoulder on the actuating rod prevents damage to the lower valve piston if it should strike the bottom of the chamber 17, forcibly. 85

The upper portion of the sleeve 3, it will be seen, has a tapered seating in the casing 1, while its cylindrical lower end is screw threaded into the casing opening. The upper end of the sleeve is diametrically slotted at 18, for engagement of a tool to screw it home, so that it shall be held firm and fixed, or to remove it. The proportions of the parts are such that when the upper edge of the upper valve head is flush with the 90 95 100 105

upper surface of the sleeve 3, the effective area of the annular opening at 13, at the upper edge of the lower valve head is right for the correct quantity of fluid to pass through at the correct pressure to be maintained for full load operation of the turbine, in accordance with the design of the nozzles 10. The upper cylindrical end of the valve casing opening wherein the sleeve 3, is mounted is of sufficient size to permit removal of the sleeve therethrough as well as of the valve 2, but is normally closed pressure tight by the cap 6, which is screw threaded thereinto. A conical abutment member 20, bears on the conical end of the upper actuating rod 15, and moves therewith, and a helically coiled compression spring 21, enclosed in the hollow cap 6, acts between the upper end thereof and the abutment member 20, to urge the valve body 2, longitudinally or endwise (downward) in the sleeve 3. Since the valve 2 takes fluid under pressure in the middle, the high temperature fluid has no access to the spring 21. As shown there is at the cap bottom a groove 22, undercut in the cap wall, and the uppermost convolution of the spring 21, is suitably enlarged and shaped into one plane, so as to engage in said groove with some degree of radial pressure and so secure the spring in the cap. The abutment member 20, interposed between the spring 21, and the valve 2, has an upturned edge portion that is bent over inward (or even pinched over) so as to overhang the corresponding end convolution of the spring (which it surrounds) and secure the member 20, to the spring. It will be seen, therefore, that when the cap 6, is unscrewed and removed, the spring 21, and the abutment member 20, come with it, and the valve 2, can at once be reached and lifted out. The spring 21 and the valve 2 are, therefore, freely removable through the opening above the mounting 3 immediately upon removal of the cap 6. The sleeve 3, is also immediately accessible for unscrewing and removal.

Into the pocket 1, extends a shaft 25, having on the remote end thereof an adjustably secured crank arm or lever 26, adapted to be controlled by the turbine governor through a connection 27, pivoted thereto at 28. Within the pocket 1, there is mounted on the shaft 25, a crank arm 30, having in its end subjacent to the valve rod 16, a screw abutment member 31, for engaging the end of said rod 16 and operating the valve 2 therethrough. As shown, provision for securing the abutment screw 31, in adjusted position is made by slitting the screw threaded lever end that carries it and providing a screw 32, for clamping the walls of the screw hole together on the abutment screw. In order to set the valve 2, it is only necessary to remove the cap 6, open the pocket

1, by removal of a cover (not shown) suitably secured to the flange 33, on the casing, loosen the screw 32, and turn the abutment screw 31, till the upper end of the upper valve head is flush with the upper end surface of the sleeve 3, and then tighten the screw 32, and replace the parts.

Into a hole in the lever 30, is hooked one end of a helical tension spring 34, for controlling and adjusting the action of the steam turbine speed governor,—which may be a centrifugal flyball governor. The convolution at the other end of this spring is squeezed together and reduced in diameter so as to take under and engage the head of a screw 35, threaded into a boss 36, on the casing 1, a jamb nut 37, being provided. A nut 38, keyed to the screw 35, below the spring 34, serves as a conveniently accessible means for turning the screw. In order to adjust the speed or voltage of the machine it is only necessary to raise or lower the screw 35, till the proper value is obtained and then tighten up the jamb nut 37.

Having thus described my invention, I claim:

1. In a turbine having a side pocket communicating with the turbine chamber, the combination of a controlling valve for motive fluid with an actuating member extending into said pocket, said valve being reversible end for end and normally tending to move inward toward said pocket; and a governor-controlled lever arm in said pocket for operating said valve through said actuating member, said lever arm having mounted and secured thereon an adjustable abutment for engaging the valve-actuating member.

2. In a turbine having a side pocket communicating with the turbine chamber, the combination of a balanced piston controlling valve taking fluid in the middle so as to nullify any effect of the fluid pressure to shift the valve in one direction or the other with an actuating member extending into said pocket; a spring acting on the opposite end of said valve from said actuating member to urge said valve toward said pocket; and a governor-controlled lever arm in said pocket for operating said valve through said actuating member.

3. A device in accordance with claim 2, in combination with an adjustment spring connected to said arm and to the wall of said side pocket.

4. In a turbine having a side pocket communicating with the turbine chamber, the combination of a valve mounting structure having an opening with a removable cap at one end thereof; a balanced piston controlling valve for motive fluid with an actuating member extending into said pocket; a governor-controlled member in said pocket for operating said valve through said actu-

ating member; and a spring acting on the opposite end of said valve from said actuating member to urge said valve endwise in said mounting; said spring and said valve 5 being freely removable through said opening upon removal of said cap.

5. In a turbine having a side pocket communicating with the turbine chamber, the combination of a balanced piston controlling valve for motive fluid with an actuating member extending into said pocket; a spring acting on the opposite end of said valve from said actuating member to urge said valve toward said pocket; a governor-controlled shaft extending through said pocket wall and a lever arm on said shaft within the pocket for operating said valve through said actuating member; and means connected to said lever arm for controlling and adjusting the action of the governor thereon.

6. In a controlling valve, the combination of a casing with a valve mounting structure therein having a removable cap at one end thereof, and an opening at the other; a removable, reversible, substantially symmetrical valve-body longitudinally movable in said casing and having an actuating rod member at either end thereof; a compression spring acting between said cap and the adjacent actuating rod of said valve-body; and means acting on the other actuating rod of said valve-body to control the position of said valve-body in said valve mounting structure.

7. A balanced piston valve body for controlling the fluid inlet of turbines comprising a pair of enlarged counter-part piston heads connected together by a reduced middle portion, and counter-part conical-ended 40 actuating rod members projecting from the two heads, whereby each of said rod mem-

bers are adapted for coaction with valve localizing members, said valve thus being symmetrical and reversible end for end in respect of all its functions.

45

8. In a controlling valve, the combination of a casing with a valve mounting structure therein, comprising a removable cap; a valve-body longitudinally movable in said structure; a coiled compression spring acting 50 between said cap as an abutment and said valve-body to urge the latter longitudinally in said structure; and a movable abutment member interposed between said spring and said valve body; said spring being secured 55 in said cap and said member secured to said spring.

9. A unitary controlling valve sub-assembly, comprising an abutment cap removable 60 from the valve casing; a coiled compression spring with one end secured in said cap; and a movable abutment member secured to the other end of said compression spring.

10. A unitary controlling valve sub-assembly, comprising a hollow abutment cap 65 removable from the valve casing and having an undercut internal groove; a coiled compression spring in said cap having a convolution engaged in said groove, so as to secure the spring in the cap; and a movable abutment member, with an overhanging portion surrounding and engaging an end convolution of the spring, so as to secure the member to the spring.

In testimony whereof, I have hereunto signed my name at Philadelphia, Pennsylvania, this eleventh day of June, 1919.

LEWIS A. DARLING.
